UNITED STATES PATENT OFFICE.

THOMAS J. McCORMICK, OF ELKO, NEVADA.

OIL-WELL UNDERREAMER.

1,401,545.

Specification of Letters Patent. Patented Dec. 27, 1921.

Application filed July 9, 1920. Serial No. 395,046.

To all whom it may concern:

Be it known that I, THOMAS J. McCORMICK, a citizen of the United States, residing at Elko, in the county of Elko and State of Nevada, have invented new and useful Improvements in Oil-Well Underreamers, of which the following is a specification.

My present invention has for its object the provision of an underreamer that is possessed 10 of an elastic quality calculated to avert "dogging" of the jaws incident to operation, and one that is characterized by other features of practical advantage.

To the attainment of the foregoing the invention consists in the improvement as hereinafter described and definitely claimed.

In the accompanying drawings, hereby made a part hereof:—

Figure 1 is a side elevation of an underreamer constructed in accordance with my invention.

Fig. 2 is a diametrical section of the same on the line 2—2 of Fig. 1, with some parts in elevation.

Fig. 3 is a section on the line 3—3 of Fig. 2, with some parts in elevation.

Fig. 4 is a horizontal section taken in the plane indicated by the line 4—4 of Fig. 2.

Fig. 5 is an enlarged section, partly in elevation, showing the manner in which I prefer to detachably fasten the cutters to the jaws.

Fig. 6 is an enlarged inverted perspective of the detent follower for coöperation with 35 the jaws.

Fig. 7 is an enlarged detail perspective showing the type of cutter that is preferably employed for soft rock.

Similar numerals of reference designate 40 corresponding parts in all of the views of the drawings.

In furtherance of my invention the body 1 of the underreamer is provided with the following features, viz: a bore 2, bifurcations 45 3, interior longitudinal guides 4 in communication with the bifurcations 3, and recesses 5, Fig. 2.

In addition to the body 1, the underreamer comprises jaws 6, jaw-expanding and cushioning means, and means to yieldingly retain the jaws when expanded or contracted. The jaw expanding and cushioning means will be readily understood when it is stated that said means in the preferred specific embodiment of my invention includes a shaft 7 movable in the bifurcations 3 of the body, anti-friction rollers 8 loose on said shaft and opposed to cam portions 9 of the jaws 6, rods 10 arranged to move rectilinearly in the guides 4 of the body and extending into the body recesses 5, and springs 11 surrounding the upper portions of said rods and interposed between nuts or other abutments 12 thereon and opposed portions 13 of the body. The jaw retaining means includes a detent follower 14 and a spring 15 backing the said detent follower. The detent follower 14 is in the form of a plate movable bodily in the body bore 2 and having at its underside two sets of grooves 16, the grooves of one set 70 being arranged to coöperate with the upper beveled end 17 of one jaw 6, and the grooves of the other set being arranged to coöperate with the beveled end 17 of the other jaw. The spring 15 of the jaw retaining means is 75 adapted to counteract or serve as a counterbalance for the springs 11 of the jaw expanding means with a view to contributing to the elastic quality of the underreamer. From this it follows that incident to the use 80 of the underreamer there is no liability of the jaws "dogging" in the hole.

In order to cause the jaws 6 to open uniformly I provide in conjunction with each of the jaws a coiled spring 18, socketed at 19 85 in the jaw and arranged on a pin 20 carried by the opposed portion of the wall of the bore 2. See Fig. 3.

In Figs. 1, 2, 3 and 5 I illustrate a portable cutter 21 designed more particularly for 90 operation against hard rock, and in Fig. 7 I illustrate a portable cutter 21^a designed more particularly for operation against soft rock. The cutters 21 differ from the cutters 21^a in that the former are toothed as indicated by 22, while the latter are blunt as indicated by 23 in Fig. 7. I designate the cutters as portable inasmuch as they render unnecessary any blacksmith operation in the field, my invention contemplating the removal of a cutter when worn or broken and the replacing of the same with a new cutter, any number of cutters being supplied. To the end that the cutters may be readily removed and this without liability of casual 100 removal or displacement while at work I resort to the construction clearly shown in Fig. 5. In the said construction the jaw 6 is provided with a bore 24 to receive a spring backed beveled detent 25, and said jaw is 110 provided in its lower end with a dovetail groove 26 for the reception of a dovetail

projection 27 of the cutter 21 and in which projection 27 is a seat 28 to receive the detent 25. Manifestly when the projection 27 is slipped endwise into the groove 26, the detent 25 will first be pressed upwardly by the action of the projection 27 against the beveled portion of the detent, and when the seat 28 is coincident with the bore 24 the detent 25 will spring into the seat and consequently will positively and safely secure the cutter to the jaw. For the ready removal of the cutter 21 I provide the same with a passage 29 through which may be introduced an implement for pressing the detent 25 upwardly against the action of the spring and retaining the detent in its retracted position while the cutter 21 is being withdrawn from engagement with the jaw 6.

It will be readily apparent from the foregoing that by virtue of the coöperation of the detent follower 14 with the upper ends 17 of the jaws, the jaws are yieldingly secured in contracted positions and also in expanded positions, the former to facilitate withdrawal of the underreamer as well as the introduction of the underreamer to its working position, and the latter to assist in preventing "dogging" of the jaws. It will also be apparent that in the working of the underreamer the contact of the jaws or the cutters thereon with the rock will have the effect of expanding the jaws notwithstanding the coöperation of the detent follower 14 with the jaws. The elastic quality ascribed to my novel underreamer is an important characteristic thereof inasmuch as the prevention of the "dogging" alluded to is calculated to greatly increase the working capacity of the underreamer.

40 In addition to the practical advantages of my novel underreamer as hereinbefore pointed out it will be noted that the underreamer is simple and inexpensive in construction, is well adapted to withstand the usage to which underreamers are ordinarily subjected, and when supplied with fresh cutters as occasion demands is adapted to last in working order for an indefinite period of time.

Having described my invention, what I claim and desire to secure by Letters-Patent, is:—

1. An underreamer comprising a body, jaws carried thereby and yielding means to cushion and expand the jaws whereby an elastic quality is imparted to the underreamer, in combination with yielding means arranged to act against the jaws counter to the first-named yielding means whereby the elastic quality of the underreamer is increased.

2. An underreamer comprising a body, jaws carried thereby and yielding means to cushion and expand the jaws whereby an elastic quality is imparted to the underreamer, in combination with yielding means

arranged to act against the jaws counter to the first-named yielding means whereby the elastic quality of the underreamer is increased, and yielding means to cause the jaws to open uniformly and thereby further increase the elastic quality of the underreamer.

3. An underreamer comprising a body, jaws carried thereby and having cam portions, movable means carried by the body to act against said cam portions, and means to yieldingly hold said movable means against downward movement and to move said movable means upwardly, in combination with means to exert yielding downward pressure on the upper ends of the jaws.

4. An underreamer comprising a body, jaws carried thereby and having cam portions, movable means carried by the body to act against said cam portions, and means to yieldingly hold said movable means against downward movement and to move said movable means upwardly, in combination with means to exert yielding downward pressure on the upper ends of the jaws, said means including a grooved detent follower, and the upper ends of the jaws being shaped to coöperate with the grooves thereof.

5. An underreamer comprising a body, jaws carried thereby and having cam portions, movable means carried by the body to act against said cam portions, and means to yieldingly hold said movable means against downward movement and to move said movable means upwardly, in combination with means to exert yielding downward pressure on the upper ends of the jaws, and means to open the jaws uniformly and to cushion the inward movements thereof.

6. An underreamer comprising a body having bifurcations, interior guide ways, and exterior recesses, a shaft movable in the said bifurcations of the body, rods movable in said guide ways of the body and connected to said shaft and having abutments disposed in the said recesses of the body, springs surrounding said rods and interposed between said abutments and opposed abutments on the body, jaws carried in the body and having cam portions, and anti-friction means mounted on the said shaft and opposed to the cam portions of the jaws.

7. An underreamer comprising a body having bifurcations, interior guide ways, and exterior recesses, a shaft movable in the said bifurcations of the body, rods movable in said guide ways of the body and connected to said shaft and having abutments disposed in the said recesses of the body, springs surrounding said rods and interposed between said abutments and opposed abutments on the body, jaws carried in the body and having cam portions, anti-friction means mounted on the said shaft and opposed to the cam portions of the jaws, a de-

tent follower movable in the bore of the body and opposed to the upper ends of the jaws, and a spring backing said detent follower.

5. An underreamer comprising a body having bifurcations, interior guide ways, and exterior recesses, a shaft movable in the said bifurcations of the body, rods movable in said guide ways of the body and connected to said shaft and having abutments disposed in the said recesses of the body, springs surrounding said rods and interposed between said abutments and opposed abutments on the body, jaws carried in the body and having cam portions, anti-friction means mounted on the said shaft and opposed to the cam portions of the jaws, a detent follower movable in the bore of the body and opposed to the upper ends of the jaws, a spring backing said detent follower, and springs in the body and exerting yielding inward pressure against the jaws.

10. An underreamer, the combination of a body, jaws carried thereby and having beveled upper ends, a detent follower mov-

able in the body and having grooves one for each jaw to coöperate with said ends of the jaws, and yielding means backing the said follower.

15. In an underreamer, the combination of a body, jaws carried thereby, and springs one for each jaw interposed between the jaws and the body and arranged to independently exert inward pressure against the upper portions of the jaws.

20. In an underreamer, the combination with a jaw having a dovetail groove in its end and also having a bore in communication with said groove, and a spring-pressed beveled detent in said bore, of a portable cutter having a dovetail projection to enter said groove, and a seat in said projection to receive said detent and also having a passage through which an instrument may be introduced to retract and hold in retracted 45 position the detent until the cutter is released from the detent.

25. In testimony whereof I affix my signature.

THOMAS J. McCORMICK.
